tion, Detroit, Mich., a corporation of Dela-
ware

Application May 4, 1932, Serial No. 609,075

53 Claims. (Cl. 51—91)

This invention relates to machines for polishing articles having surfaces which are curved with respect to longitudinal and transverse planes of reference, for example, automobile lamp housings having paraboloidal surfaces.

It is among the objects of the present invention to provide a machine which will support an article and cause the same to be moved with respect to an ordinary buffing wheel in a manner such that the article will be polished completely and effectively in the shortest space of time.

The herein disclosed machine, constituting an embodiment of the present invention, comprises a work-holder for receiving an article and for rotating the same about its longitudinal axis while in contact with a rotary buffing wheel, means operating while the article is rotating about its own axis for rocking the article about an axis transverse to its axis of rotation and parallel to the axis of the buffing wheel and for causing relative linear movement between the article and the buffing wheel transverse to the axis of the buffing wheel, the rocking of the article and the relative linear movement between the article and the buffing wheel resulting in engagement of the buffing wheel periphery with consecutive portions of the curved surface of the article.

Further objects and advantages of the present invention will be apparent from the following description, reference being had to the accompanying drawings wherein a preferred embodiment of one form of the present invention is clearly shown.

In the drawings:

Fig. 1 is a perspective view of a machine embodying the present invention.

Fig. 2 is a top view of this machine.

Fig. 3 is a front elevation of the machine showing certain parts in section, the sections being taken substantially on the lines 3a—3a and 3b—3b of Fig. 2.

Fig. 4 is a front elevation of the machine.

Fig. 5 is an enlarged fragmentary sectional view taken substantially along the line 5—5 of Fig. 9.

Fig. 6 is a view similar to Fig. 3 showing, however, certain parts removed so as to disclose certain mechanisms.

Fig. 7 is a view similar to Fig. 6, and showing the position of certain elements of the machine at the beginning of a polishing operation.

Fig. 8 shows such certain elements of the machine at an advanced state of the polishing operation.

Fig. 9 is a sectional view taken substantially along the line 9—9 of Fig. 2.

Fig. 10 is a sectional view taken on the line 10—10 of Fig. 9.

Fig. 11 is an enlarged sectional view taken on the line 11—11 of Fig. 9.

Fig. 12 is a fragmentary sectional view taken substantially along the line 12—12 of Fig. 3.

Fig. 13 is a fragmentary sectional view taken substantially on the line 13—13 of Fig. 3.

Fig. 14 is a sectional view taken on the line 14—14 of Fig. 3.

Fig. 15 is a fragmentary elevation looking in the direction of arrow 15 in Fig. 9.

Fig. 16 is an enlarged view of the clutch shifting mechanism disclosed in Fig. 15, and shows the clutch in engaging position.

Fig. 17 is a view similar to Fig. 16 showing the clutch disengaged, however.

Fig. 18 is a fragmentary sectional view taken substantially along the line 18—18 of Fig. 15.

Figs. 19 and 20 are diagrammatic views illustrating the manner in which the cross-slide is moved relative to its support.

Referring to Figs. 9 and 12, a machine frame 20 or base 20 is shown having a cylindrical portion 21 which provides a bore 22 having a groove 23 extending longitudinally throughout the said bore. A rectangularly threaded stub shaft 24 is rotatably supported within the bore 22 and terminates into a disc-like head 25 which is located in an annular recess 26 of a support 27 and secured thereto by a plurality of screws 28. The stub shaft 24 carries a key 29 which slides in the groove 23 of the base in order to prevent rotation of the stub shaft relative to the base. A hand wheel 30, having an interiorly threaded boss 31, rests against the annular boss 21 of the base and is threadedly received by the stub shaft 24. Upon rotation of the handwheel 30 the stub shaft 24 is caused to move axially, thus making it possible to adjust the height of the support 27 relative to base 20.

The support 27 provides guide ways 35 and ball bearings 36 for movably supporting a slide 37 which provides guide ways for a table 38 for movement transverse of the direction of movement of the slide 37 relative to the base. As best shown in Fig. 4, the table 38 has an extension 39 rotatably supporting a threaded spindle 40, carrying a hand wheel 41 and threadedly received by a nut 42 secured to the slide 37 in any suitable manner such as welding, for instance. Rotation of the hand wheel 41 effects movement of the table 38 in the guide ways of the slide 37 relative

thereto. A bracket 45, comprising two chambers 45a and 46a separated from each other by a partition 47a, is supported by the table 38 and guided for movement transverse to the direction of movement of the slide 37 relative to the base within guide ways 46, provided by the table 38 as best shown in Fig. 9. Coverplate 48a and 49a close the chambers 45a and 46a, respectively, of the bracket 45 and are secured to the bracket by 10 screws 50a. The bracket 45 provides two parallel ribs 50 and 51 which provide bearings 52 and 53 for cylindrical stubs 54 and 55 respectively, secured to a casing 56 in any suitable manner. (See Fig. 13). This casing provides two ball 15 bearings 57 and 58 for journaling a horizontal shaft 59 which end extending beyond the bearing 53 is furthermore journalled in a bushing 60 located in the bearing 60a of a housing 61 which is integral with the rib 51 as shown in Fig. 13. 20 The casing 56 is covered by a plate 62 and secured thereto by screws 63. The casing 56 and the cover plate 62 provide annular recesses 64 and 65, respectively, wherein ball bearings 66 and 67, respectively, are located which support a partially hollow stub shaft 68 for rotation about an axis transverse of the axis of shaft 59. The stub shaft 68 has a shoulder 69 which rests against ball bearing 67. A ring 70, secured to the cover plate 62 by screws 71 retains said ball bearing in recess 30 65 of the cover plate, while a nut 72, threaded over the end of stub shaft 68 maintains ball bearing 66 within recess 64 of the casing. A workholder 73, resembling the interior contour of an auto lamp housing is journalled coaxially 35 of that part of stub shaft 68 which extends beyond the cover plate 62 and is held in firm engagement with a shoulder 75 of said stub shaft by a screw 74.

40 Means for rotating the workholder

Referring to Figs. 3, 13 and 14, an electric motor 80 (Fig. 3) supported by the bracket 45 and secured thereto in any suitable manner. The end of shaft 59 which extends beyond the bushing 60 has a sprocket wheel 82 keyed thereto. A nut 83, received by the threaded end of shaft 59 which extends beyond said sprocket wheel maintains the same in proper position on the shaft. A chain 84 drivingly connects the sprocket wheel 50 with the motor. A worm 85 which is keyed to shaft 59 intermediate the ball bearings 57 and 58 and held in engagement with the shoulder 86 of said shaft by a spacing collar 87, meshes with a worm gear 88, keyed to stub shaft 68 as at 89. 55 The worm gear is held in engagement with a shoulder 90 of stub shaft 68 by a spacing washer 91 which rests on ball bearing 66, thus preventing longitudinal movement of the worm gear relative to the stub shaft and insuring proper meshing of the worm gear with the cooperating worm at all times.

60 Mechanism for moving the bracket relative to the table

65 Referring to Figs. 4, 13 and 15 to 18 inclusive, worm 100, integral with the shaft 59 is meshing with a worm gear 101, fixed to a shaft 102 which is journalled in a bearing 103, provided by an annular boss 104 of the casing 61. The end of shaft 102 which extends beyond the casing 61 is splined and receives a shiftable clutch member 105 which cooperates with a clutch member 106 fixed to a shaft 107, journalled in a bearing 108 which 70 is provided by an annular boss 109 of the bracket 75

45. The free end of shaft 107 carries a bevel pinion 110 which is in mesh with a bevel gear 111, keyed to a shaft 112 as at 113, which shaft is journalled in bearings 114 and 115, provided by the partition 47a of the bracket 45 and by the 5 coverplate 49a, respectively. Axial thrust of the bevel gear 111 is taken up by a flared portion 116 of the bearing 114 which is engaged by the hub 117 of said bevel gear. A nut 118 which is threaded over a portion of shaft 112 maintains 10 the bevel gear in engagement with the flared portion 116 of the bearing 114. Referring more particularly to Figs. 6, 7 and 8, one end of a lever 119 is pivoted to the bracket 45 as at 120, the other end of said lever is connected with the extension 39 of the table 38 by a link 121 passing through an opening 122 of the bracket 45. The lever 119 carries an antifriction roller 123, co-operating with a cam plate 124 which is keyed to the shaft 112. Clamped to the extension 39 of 20 the table 38 by a plate 125 screwed onto said extension as at 126 is a cable 127, shown in Fig. 1, which passes through a side wall of the bracket into chamber 46a where it is guided over a pulley 128, rotatably supported by a stud 128a fixed to 25 the bracket, then passes again through said side wall of the bracket out of chamber 46a and finally guided over another pulley 129 which is rotatably supported on the extension 39 of the table 38. A weight 130 is attached to the free end of the cable 30 127 as at 131 shown in Fig. 1. The weight 130 tends to move the bracket 45 relative to the table and toward its extension 39. This tendency of the weight causes the cam plate 124 to maintain 35 in engagement with the cam roller 123 as will appear obvious later. Upon rotation of the cam plate 124 the lever 119 is rocked about the pivot connection 132 between said lever and the link 121 which connection is in reality a floating center for the movement of the lever 119. It follows 40 from the foregoing that upon rocking of the lever 119, initiated by the rotation of the cam plate 124, the pivot connection 120 between said lever and the bracket 45 is caused to move, which movement expresses itself as movement of the bracket 45 relative to the table 38.

50 Mechanism for rocking the workholder supporting casing

Referring to Figs. 6, 7, 8 and 9, the casing 56 comprises a lug 140 which is connected with a bell crank lever 141, pivoted to the bracket 45 as at 142, by a lengthwise adjustable link 143. The bell crank lever 141 carries an anti-friction roller 144, cooperating with a cam plate 145 which is keyed to the shaft 112. It will be noticed from the drawings that the greater mass of the casing 56 and the entire mass of the workholder tends to rotate the casing clockwise as viewed in 55 Fig. 6 about its pivot support in the bearings 52 and 53, and therefore maintains the roller 144 in engagement with the cam plate 145 at all times. In order to prevent dust and other foreign substance from entering the chamber 46a of the bracket 45 through an opening 146 which is necessary for the passage of the link 143, a plate 147 which closely embraces the link 143 is held in sliding engagement with a surface 148 of the bracket 45 by a plate 149, secured to said bracket by screws 150, thus intercepting communication of the opening 146 with the outside regardless of the bodily movement of the connecting link 143.

Mechanism for moving the table relative to the support

Referring to Fig. 3 and particularly to Fig. 9, a bevel gear 160 is shown keyed to the end of shaft 112 which extends beyond the cover 49a; a washer 161 and a screw 162 received by said shaft maintain said bevel gear in engagement with a spacing washer 161a which rests against the shaft bearing 115. A second bevel gear 163 which is in mesh with bevel gear 160 is fixed to a stub shaft 164 by a pin 165. The stub shaft 164 is journalled in an annular boss 166 of a housing 167 formed integral with the cover 49a. A collar 168, fixed to the stub shaft 164 by a set screw 169 prevents axial movement of said shaft. As best shown in Figs. 3, 9 and 12, a casing 170, integral with the slide 37 houses a gear 171, fixed to a hub 172 by a set screw 173, which hub in turn is journalled on a stud 174 having a threaded portion 175 which extends through said casing and receives a nut 176 drawing shoulder 177 of the stud into firm engagement with the casing 170 thus rigidly securing the stud to the casing. Another gear 178 also being housed within the casing 170 and meshing with gear 171 is keyed as at 180 to a stub shaft 179 which is journalled in bearing 181 and 182, provided by the casing 170. The free end of stub shaft 179 which extends beyond the casing 170 has keyed thereto as at 184 a crank arm 185 which is also pivoted as at 186 to an arm 187 of a ring plate or link 188, journalled on a cylindrical portion 189 of the support 27. A retainer ring 190, secured to said support by screws 191 maintains the ring plate 188 in proper position on the support as shown in Fig. 12. Telescoping members 192 and 193 are drivingly connected with the stub shaft 164 through a universal joint 194 and with the stud 174, respectively, by a universal joint 195. As shown in Fig. 11, the member 192 provides a plurality of longitudinal semicircular grooves 196 in its periphery which receive a plurality of balls 197 also located in longitudinal semicircular interior grooves of the member 193. This driving connection between the stub shaft 164 and the stud 174 allows for movement of the bracket 45 relative to the table 38 during polishing operations and also allows for adjustment of the table 38 relative to the slide 37 as can be readily understood.

With special reference to Figs. 19 and 20 wherein reference numerals of already described elements appear on diagrammatically illustrated equivalents, it will be noticed that rotation of the gear 171 results in rotation of the gear 178 and of the crank arm 185 about the axis of shaft 179. Since the pivot point 186 of the crank arm is also a point of the ring plate 188 which is journalled on the stationary support 27 it follows that the slide 37 is bound to move relative to the support 27 in a continuously changing path. The slide 37 is, however, guided by the support 27 for movement in one direction X only, the imaginary resulting movement R of the slide at every instance is therefore resolved into components C₁ and C₂. C₁ constitutes the actual movement of the slide relative to the support and within the guideways thereof, while C₂ expresses itself in rotation of the ringplate 188 about its journal on the support. Gears 171, 178 may be replaced by another set of gears of a different ratio whereby to vary the number of reciprocations of slide 37 relative to support 27 for instance. If such a ratio change is not desired, the

telescoping driving members 192 and 193 can be directly connected with stub shaft 179 in the same manner as they are shown connected with stud 174 in Fig. 9 and the meshing gears can be dispensed with as can be readily understood. 5

Clutch control mechanism

Referring to Figs. 4, 9 and 15 to 18 inclusive, a clutch shifter rod 200 is shown engaging the shiftable clutch half 105 and being journalled on a 10 shaft 201 which in turn is journalled in bearings 202 and 203, provided by the bracket 45. A latch plate 204 is secured to the clutch shifter rod by a screw 205 and located thereon by pins 206. A latch lever 207, pivoted to the bracket 45 as at 208 15 is urged into engagement with said latch plate by its own gravity and is tripped out of engagement with the latch plate by any one of a plurality of equally spaced cammed fingers 209, pressfitted into the periphery of a control disc 210 which is 20 supported on the hub 211 of a gear 212 coaxially thereof. The gear 212 is journalled on a stud 213 which is secured to the cover plate 48a. The control disc 210 is secured on the gear 212 by a plurality of screws 214 in order that the gear and the 25 control disc rotate in unison. The gear 212 meshes with a pinion 215 mounted on a reduced portion of shaft 112, which free end is journalled in a bearing 216, provided by the cover 48a. Fixed to the shaft 201 as at 217 and in close proximity to 30 the latch plate 204 is another latch plate 218 which is also engaged by the latch lever 207. Keyed to the end of shaft 201 which extends beyond the bearing 202 is a lever 219 which carries a weight 220. The shaft 201 carries a key 221 35 which projects into a wide groove 222 of the hub 223 of the clutch shifter rod. In order to move the clutch shifter rod from clutch disengaging position as shown in Fig. 17 into clutch engaging position, the operator will rock the weighted lever 40 219 clockwise as viewed in Fig. 15. During such clockwise movement of the lever 219 the key 221 will engage a side wall 224 of the groove 222 in the hub of the clutch shifter rod thus causing the latter to follow the lever 219 until the latch lever 45 207 engages the latch plate 204 of the clutch shifter rod and the latch plate 218 on the shaft 201 at which time the shiftable clutch half has arrived in clutch engaged position. The latch lever 207 maintains the lever 219 in raised position and also maintains the clutch shifter rod in 50 clutch engaging position against the tension of a spring 225 which is interposed between an arm 226 of the clutch shifter rod and the bottom of bracket 45. Upon tripping of the latch lever 207 55 by one of the cammed fingers 209 of the control disc 210, the clutch shifter rod will be released and moves into clutch disengaging position under the tension of spring 225. Concurrently with the clutch shifter rod the latch plate 218 is released 60 which allows the weighted lever 219 to drop counterclockwise until the key 221 engages another side wall 227 of the groove 222 of the clutch shifter rod which in the meantime has come to rest in clutch disengaging position. The short period 65 which elapses between the tripping of the latch lever 207 and the actual disengaging of the clutch is sufficient to move the tripping finger 209 on the control disc out of engagement with the latch lever 207 after tripping of the same. 70

Workpiece gripping device

Referring now to Figs. 1, 6, 13 and 14 a plurality of forked lugs 230 integral with the workholder 73, pivotally support grippers 231 as at 232 75

which clamp the rim of an auto lamp housing onto wear plates 233, carried by the forked lugs as best shown in Figs. 7 and 8. The grippers 231 have ball ends 234 which ride in an annular 5 groove 235 of a collar 236, journaled on shaft 68 and drivingly connected therewith by a pin 237 which extends through an oblong recess 238 in the hollow part of said shaft. A rod 239 which slides within the hollow portion of the shaft 68 is hinged 10 on the pin 237 and extends beyond ball bearing 66 in the casing 56. A cup-shaped member 240 is secured to said casing in any suitable manner and provides a guide for the rod 239. A spring 241, interposed between a shoulder 242 of the rod 15 239 and a hollow plug 243 through which the rod 239 extends and which is threaded into the cup-shaped member 240, tends to maintain the pin 237 in the position shown in Fig. 14. From this follows that the spring 241 tends to shift the grippers 231 into gripping position. Pivoted to the lug 140 of the casing 56 is a lever 244 which forked ends extend to both sides of the rod 239. The lever 244 rests on a nut 245 which is threaded over the end of rod 239 extending beyond the lever 244 20 and is held in adjusted position thereon by a lock nut 246. The free end of the forked lever 244 is connected by a chain 247 with a foot pedal 248 pivoted to a bracket 249 on the base 20. The chain is secured to the foot pedal so as to be just 25 sufficiently slack to allow the grippers to maintain a gripping position while the workholder axis is in a vertical position as shown in Fig. 1 or 6. When the operator depresses the pedal, the chain will at once become tight and rock the lever 244 clockwise as viewed in Fig. 6 which causes the rod 239 and the gripper shifting collar 236 to move in such direction as to rock the grippers clockwise as viewed in Fig. 6 or 14, whereupon the operator removes a lamp housing from the workholder and 30 places a new lamp housing thereon.

Mode of operation

Suppose the machine is at rest, the operator steps on the pedal 248, removes a polished lamp 45 housing from the continuously rotating workholder and places a new lamp housing upon the same, whereupon he releases the foot pedal thereby releasing the grippers 230 which are yieldingly urged into lamp housing gripping position. Immediately thereafter the operator raises the weighted lever 219 for drivingly engaging the clutch halves 105, 106, drivingly connecting the motor 80 with the cam shaft 112 for two complete revolutions of the latter. Two complete 50 revolutions of the cam plate 124 on the cam shaft effect movement of the bracket 45 in the guide-ways of the table 38 toward and away from a rotary buffering wheel 260 and more particularly from position A indicating the resting position of 55 the table in Figs. 6 and 7, to position B, then to position C, from there back to position B and then to position A again, at which time cam 124 completed one revolution. During the second revolution of this cam a repetition of the above 60 described movement of the bracket takes place. Cam plate 145, being also mounted on the cam shaft 112 starts to rotate concurrently with cam plate 124 and is so designed that it rocks the workholder when the bracket reaches position B 65 after moving from the resting position A to position B. During the movement of the bracket from position B to position C, the cam plate 145 rocks the workholder clockwise in such manner that the lamp housing substantially rolls on the 70 polishing surface of the buffering wheel. Fig. 8

shows the position of the lamp housing relative to the continuously rotating buffering wheel at the end of the clockwise rotation of the workholder. During the movement of the bracket from position C to position B the cam plate 145 5 rocks the workholder counter-clockwise again substantially to roll the lamp housing on the buffering wheel polishing surface until the dot and dash position of the workholder as shown in Fig. 7 is reached at which time cam plate 145 10 has completed one revolution. During the second reciprocation of the bracket from position B to C and back again to B the cam plate 145 again rocks the workholder in the same manner described in connection with the first reciprocation of the bracket from position B to position C and back to position B again. At the end of the second rocking of the workholder the same reaches the dot and dash position in Fig. 7 again whereupon cam plate 145 has no further rocking 20 effect on the workholder in spite of its continued rotation.

During the two revolutions of the cam shaft 112 the crank arm 185 is also rotated twice due to the ratio 1 to 1 between the bevel gears 160, 25 163 and the gears 171, 178. Rotation of the crank arm 185 effects movement of the slide 37 and therewith bracket 45 relative to the support 27 in a direction transverse of the direction of movement of the bracket relative to the table 38 30 or slide 37 which is stationary with respect to the former. The two revolutions of the crank arm effect two reciprocations of the slide 37 relative to the support 27 so that the lamp housing, while being in engagement with the buffering wheels 35 is moved across the buffering wheel surface in order to utilize the entire width of the same.

Since the ratio between gear 215 on the cam shaft and gear 212 is 1 to 6 and because the control disc 210 carries three equally spaced cammed 40 latch tripping fingers 209, it follows that it takes two revolutions of gear 215 on the cam shaft to move a cammed finger 209 into latch lever tripping position. Upon tripping of the latch lever 207 the clutch shifter rod 200 is released and 45 urged into clutch disengaging position by spring 225; concurrently with the clutch shifter rod the weighted lever 219 is also released and drops down into the position shown in Fig. 15, ready to be lifted again by the operator to start another 50 polishing operation after removing the polished lamp housing from the workholder and placing another housing thereon.

It is to be understood that this invention is not limited to two complete revolutions of the cam 55 shaft for one polishing operation on a lamp housing, a properly designed cam and introduction of additional speed reducing elements between the motor and the cam shaft could produce the described movements of the workholder relative to the buffering wheel in the same period of time in response to one revolution of the cam shaft.

While the form of embodiment of the present invention as herein disclosed, constitutes a preferred form, it is to be understood that other 65 forms might be adopted, all coming within the scope of the claims which follow.

What is claimed is as follows:

1. A machine for polishing the curved surface of a workpiece comprising, in combination, a 70 rotary buffering wheel; means for rotating the workpiece about the axis of the curved surface thereof; means for rocking the workpiece about an axis transverse to its axis of rotation and parallel to the buffering wheel axis; means for ef- 75

fecting relative movement between the buffing wheel and the workpiece at right angles to the rocking axis of the latter; and means for effecting relative movement between the buffing wheel and the workpiece parallel to the rocking axis of the latter.

2. A machine for polishing the curved surface of a workpiece comprising, in combination, a rotary buffing wheel; means for rotating the workpiece about the axis of the curved surface thereof; and simultaneously actuating means for rocking the workpiece about an axis transverse to its axis of rotation and parallel to the axis of the buffing wheel and causing linear relative movement between the workpiece and the buffing wheel transversely of the axis of the latter, such rocking of the workpiece and relative linear movement between the latter and the buffing wheel resulting in a successive engagement of the periphery of the buffing wheel with consecutive portions of the contour of the curved workpiece surface.

3. A machine for polishing the curved surface of a workpiece comprising, in combination, a rotary buffing wheel; means for rotating the workpiece about the axis of the curved surface thereof; simultaneously actuating means for rocking the workpiece about an axis transverse to its axis of rotation and parallel to the axis of the buffing wheel and causing linear relative movement between the workpiece and the buffing wheel transversely of the axis of the latter, such rocking of the workpiece and relative linear movement between the latter and the buffing wheel resulting in a successive engagement of the periphery of the buffing wheel with consecutive portions of the contour of the curved workpiece surface; and means for causing relative movement between the workpiece and the buffing wheel parallel to the axis of the latter.

4. A machine for polishing the curved surface of a workpiece comprising, in combination, a rotary buffing wheel; means for rotating the workpiece about the axis of the curved surface thereof; simultaneously actuating means for rocking the workpiece about an axis transverse to its axis of rotation and parallel to the axis of the buffing wheel transversely of the axis of the latter, such rocking of the workpiece and relative linear movement between the latter and the buffing wheel resulting in a successive engagement of the periphery of the buffing wheel with consecutive portions of the contour of the curved workpiece surface; and means for moving the workpiece relative to the buffing wheel parallel to the axis of the latter.

5. A machine for polishing the curved surface of a workpiece comprising, in combination, a rotary buffing wheel; means for rotating the workpiece about the axis of the curved surface thereof; means for rocking the workpiece about an axis transverse to its axis of rotation and parallel to the buffing wheel axis; means for effecting relative movement between the buffing wheel and the workpiece at right angles to the rocking axis of the latter; and means for bodily moving the workpiece parallel to its rocking axis.

6. A machine for polishing the curved surface of a workpiece comprising, in combination, a rotary buffing wheel; means for rotating the workpiece about the axis of the curved surface thereof; means for rocking the workpiece about an axis transverse to its axis of rotation and parallel to the buffing wheel axis; means for bodily mov-

ing the workpiece at right angles to its rocking axis; and means for effecting relative movement between the buffing wheel and the workpiece parallel to the rocking axis of the latter.

7. A machine for polishing the curved surface of a workpiece comprising, in combination, a rotary buffing wheel; means for rotating the workpiece about the axis of the curved surface thereof; means for rocking the workpiece about an axis transverse to its axis of rotation and parallel to the buffing wheel axis; means for bodily moving the workpiece at right angles to its rocking axis; and means for bodily moving the workpiece parallel to its rocking axis.

8. A machine for polishing the curved surface of a workpiece comprising, in combination, a rotary buffing wheel; means for rotating the workpiece about the axis of the curved surface thereof; and simultaneously actuating means for rocking the workpiece about an axis transverse to its axis of rotation and parallel to the axis of the buffing wheel and for moving the workpiece transversely of the buffing wheel axis, such rocking and moving of the workpiece resulting in a successive engagement of the periphery of the buffing wheel with consecutive portions of the contour of the curved workpiece surface.

9. A machine for polishing the curved surface of a workpiece comprising, in combination, a rotary buffing wheel; means for rotating the workpiece about the axis of the curved surface thereof; simultaneously actuating means for rocking the workpiece about an axis transverse to its axis of rotation and parallel to the axis of the buffing wheel and for moving the workpiece transversely of the axis of the buffing wheel, such rocking and moving of the workpiece resulting in a successive engagement of the periphery of the buffing wheel with consecutive portions of the contour of the curved workpiece surface; and means for causing relative movement between the workpiece and the buffing wheel parallel to the axis of the latter.

10. A machine for polishing the curved surface of a workpiece comprising, in combination, a rotary buffing wheel; means for rotating the workpiece about the axis of the curved surface thereof; and simultaneously actuating means for rocking the workpiece about an axis transverse to its axis of rotation and parallel to the buffing wheel axis, for linearly moving the workpiece transversely of the buffing wheel axis and for moving the workpiece parallel to the buffing wheel, such rocking and moving of the workpiece resulting in engagement of consecutive portions of the periphery of the buffing wheel with consecutive portions of the contour of the curved workpiece surface.

11. A polishing machine of the character described comprising, in combination, a rotary buffing wheel; a machine frame; a slide supported by the machine frame for movement parallel to the axis of the buffing wheel; a bracket supported by the slide for movement transverse to the axis of the buffing wheel; a rotatable workholder pivotally mounted on the bracket; a prime mover; means drivingly connecting the prime mover with the workholder for rotating the same; means for rocking the workholder about its pivotal support; means for moving the bracket; and means actuated by the prime mover for moving the slide.

12. A polishing machine of the character described comprising, in combination, a rotary buffing wheel; a machine frame; a slide supported

means actuated by the prime mover for moving the slide; and means for rendering the slide moving means and the workholder rocking means inoperative after completion of a polishing operation.

22. In a polishing machine of the character described, the combination of a machine frame; a slide supported by the machine frame for linear movement; a bracket supported by the slide for movement transverse to the direction of linear movement of the slide; a rotatable workholder pivotally mounted on the bracket; a prime mover; means drivingly connecting the prime mover with the workholder for rotating the same; means actuated by the prime mover for rocking the workholder about its pivot support; means actuated by the prime mover for moving the bracket; means actuated by the prime mover for moving the slide; and means for rendering the bracket moving means, the slide moving means and the workholder rocking means inoperative after completion of a polishing operation.

23. A polishing machine of the character described comprising, in combination, a rotary buffing wheel; a machine frame; a slide supported by the machine frame for movement parallel to the axis of the buffing wheel; a bracket supported by the slide for movement transverse to the axis of the buffing wheel; a rotatable workholder pivotally mounted on the bracket; a prime mover; means drivingly connecting the prime mover with the workholder for rotating the same; means for rocking the workholder about its pivotal support; means actuated in response to operation of the last said means for moving the bracket relative to the slide; and means actuated by the prime mover for moving the slide relative to the machine frame.

24. A polishing machine of the character described comprising, in combination, a rotary buffing wheel; a machine frame; a slide supported by the machine frame for movement parallel to the axis of the buffing wheel; a bracket supported by the slide for movement transverse to the axis of the buffing wheel; a rotatable workholder pivotally mounted on the bracket; a prime mover; means drivingly connecting the prime mover with the workholder for rotating the same; means actuated by the prime mover for rocking the workholder about its pivotal support; means actuated in response to operation of the last said means for moving the bracket relative to the slide; and means actuated by the prime mover for moving the slide relative to the machine frame.

25. In a polishing machine of the character described, the combination of a machine frame; a slide supported by the machine frame for linear movement; a bracket supported by the slide for movement transverse to the direction of movement of the slide; a rotatable workholder pivotally mounted on the bracket; a prime mover; means drivingly connecting the prime mover with the workholder for rotating the same; a device for rocking the workholder; a device for moving the bracket; a rotatable shaft; means on the shaft for actuating all devices in timed relation with each other; and means for moving the slide relative to the frame.

26. In a polishing machine of the character described, the combination of a machine frame; a slide supported by the machine frame for linear movement; a bracket supported by the slide for movement transverse to the direction of movement of the slide; a rotatable workholder pivotally mounted on the bracket; a prime mover;

means drivingly connecting the prime mover with the workholder for rotating the same; a device for rocking the workholder; a device for moving the bracket relative to the slide; a rotatable shaft; means on the shaft for actuating all devices in timed relationship with each other; and means actuated in timed relationship with the operation of the devices for moving the slide relative to the frame.

27. In a polishing machine of the character described, the combination of a machine frame; a slide supported by the machine frame for linear movement; a bracket supported by the slide for movement transversely of the direction of movement of the slide; a rotatable workholder pivotally mounted on the bracket; a prime mover, means drivingly connecting the prime mover with the workholder for rotating the same; a device for rocking the workholder; a device for moving the bracket; a rotatable shaft; means on the shaft for actuating all devices in timed relation with each other; means for moving the slide relative to the frame; and means for drivingly connecting the shaft with the prime mover.

28. In a polishing machine of the character described, the combination of a machine frame; a slide supported by the machine frame for linear movement; a bracket supported by the slide for movement transversely of the direction of movement of the slide; a rotatable workholder pivotally mounted on the bracket; a prime mover; means drivingly connecting the prime mover with the workholder for rotating the same; a device for rocking the workholder; a device for moving the bracket; a rotatable shaft; means on the shaft for actuating all devices in timed relation with each other; means for moving the slide relative to the frame; means for drivingly connecting the rotatable shaft with the prime mover; and means for automatically disconnecting the shaft from the prime mover after a completed polishing operation.

29. In a polishing machine of the character described, the combination of a machine frame; a slide supported by the machine frame for linear movement; a bracket supported by the slide for movement transversely of the direction of movement of the slide; a rotatable workholder pivotally mounted on the bracket; a prime mover; means drivingly connecting the prime mover with a workholder for rotating the same; a device for rocking the workholder; a device for moving the bracket; a rotatable shaft; means on the shaft for actuating all devices in timed relation with each other; means actuated in timed relation with the operation of the devices for moving the slide relative to the frame; means for drivingly connecting the rotatable shaft with the prime mover; and means for automatically disconnecting the shaft from the prime mover after a completed polishing operation.

30. In a polishing machine of the character described, the combination of a machine frame; a slide supported by the machine frame for linear movement; a bracket supported by the slide for movement transversely of the direction of movement of the slide; a rotatable workholder pivotally mounted on the bracket; a prime mover; means drivingly connecting the prime mover with the workholder for rotating the same; a device for rocking the workholder; a device for moving the bracket; a rotatable shaft carried by the bracket; means on the shaft for actuating all devices in timed relation with each other; and means for moving the slide relative to the frame.

31. In a polishing machine of the character described, the combination of a machine frame; a slide supported by the machine frame for linear movement; a bracket supported by the slide for movement transversely of the direction of movement of the slide; a rotatable workholder pivotally mounted on the bracket; a prime mover; means drivingly connecting the prime mover with the workholder for rotating the same; a device for rocking the workholder; a device for moving the bracket, a rotatable shaft; cams on the shaft for actuating all devices; and means for moving the slide relative to the frame.

32. In a polishing machine of the character described, the combination of a machine frame; a slide supported by the frame for movement in a certain direction; a bracket supported by the slide for movement in another direction; a device for moving the bracket on the slide; a rotatable shaft carried by the bracket; means on said shaft for actuating the device; and means driven by said shaft for moving the slide relative to the frame.

33. In a polishing machine of the character described, the combination of a machine frame; a slide supported by the frame for movement in a certain direction; a bracket supported by the slide for movement in another direction; a rotatable workholder pivotally mounted on the bracket; a device for moving the bracket relative to the slide; a device for rocking the workholder about its pivot axis; a rotatable shaft carried by the bracket; means on said shaft for actuating all devices; and means driven by said shaft for moving the slide relative to the frame.

34. In a polishing machine of the character described, the combination of a machine frame; a slide supported by the frame for movement in a certain direction; a bracket supported by the slide for movement in another direction; a device for moving the bracket relative to the slide; a rotatable shaft carried by the bracket; means on said shaft for actuating the device; means actuated in response to rotation of the shaft for moving the slide relative to the frame; a prime mover, a driving connection between the prime mover and the shaft, said driving connection including a clutch; means for actuating the clutch; and means actuated in response to a predetermined cycle of rotation of the shaft for causing the clutch actuating means to disengage the clutch.

35. In a polishing machine of the character described, the combination of a machine frame; a slide supported by the frame for movement in a certain direction; a bracket supported by the slide for movement in another direction; a rotatable workholder pivotally mounted on the bracket; a device for moving the bracket relative to the slide; a device for rocking the workholder about its pivot axis; a rotatable shaft carried by the bracket; means on said shaft for actuating all devices; means actuated in response to rotation of the shaft for moving the slide relative to the frame; a prime mover; a driving connection between the prime mover and the shaft, said driving connection including a clutch; means for actuating the clutch; and means actuated in response to a predetermined cycle of rotation of the shaft for causing the clutch actuating means to disengage the clutch.

36. In a polishing machine of the character described, the combination of a machine frame; a slide supported by the machine frame for linear movement; a bracket supported by the slide for

movement transversely of the direction of movement of the slide; a rotatable workholder pivotally mounted on the bracket; a prime mover carried by the bracket; means drivingly connecting the prime mover with the workholder for rotating the same; a device for rocking the work holder; a device for moving the bracket; a rotatable shaft carried by the bracket; means on the shaft for actuating all devices in timed relation with each other; means for moving the slide relative to the frame; means for drivingly connecting the prime mover with the shaft; and means for automatically disconnecting the prime mover from the shaft after completion of a polishing operation.

37. In a polishing machine of the character described, the combination of a machine frame; a bracket supported by the frame for movement in a certain direction; a rotatable workholder pivotally mounted on the bracket; a device for moving the bracket relative to the frame; a device for 20 rocking the workholder about its pivot axis; a rotatable shaft carried by the bracket; means on said shaft for actuating all devices; a prime mover carried by the bracket; a driving connection between the prime mover and the shaft, said driving connection including a normally disengaged clutch; means for shifting the clutch into engaged position; means for arresting the clutch in engaged position; and means actuated in response to a predetermined cycle of rotation of the shaft 30 for causing the clutch arresting means to release the clutch.

38. In a polishing machine of the character described, the combination of a machine frame; a bracket supported by the frame for movement in a certain direction; a rotatable workholder pivotally mounted on the bracket; a device for moving the bracket relative to the frame; a device for 25 rocking the workholder about its pivot axis; a rotatable shaft carried by the bracket; means on said shaft for actuating all devices; a prime mover carried by the bracket; a driving connection between the prime mover and the shaft, said driving connection including a normally disengaged clutch; means for shifting the clutch into engaged position; a lever pivotally mounted on the bracket and normally arresting the clutch in engaged position; meshing gears of a predetermined ratio rotatably carried by the bracket, one being rotatable with the shaft and another having a 50 plurality of equiangularly spaced extending fingers, each for tripping the lever out of clutch arresting position upon engagement with the same.

39. In a polishing machine of the character described; the combination of a machine frame; a slide supported by the machine frame for movement in a certain direction; a bracket supported by the slide for movement in another direction; a rotatable shaft carried by said bracket; a rotatable workholder pivotally mounted on the bracket; a prime mover; means drivingly connecting the prime mover with the workholder for rotating the same; means on the shaft for rocking the workholder; means for moving the bracket relative to the slide; means on the shaft for actuating the last said means; means actuated by the shaft for moving the slide relative to the machine frame; means drivingly connecting the prime mover with the shaft; and means for rendering the last said means ineffective after completion of a polishing operation.

40. A polishing machine of the character described comprising, in combination, a rotary buffing wheel; a machine frame; a slide supported by the machine frame for movement parallel to

- the axis of the buffing wheel; a bracket supported by the slide for movement transverse to the axis of the buffing wheel; a prime mover carried by the bracket; a rotatable shaft carried by the bracket; means for moving the slide relative to the machine frame; means drivingly connecting the last said means with the shaft; a rotatable workholder pivotally mounted on the bracket; means drivingly connecting the prime mover with the workholder for rotating the same; means on the shaft for rocking the workholder about its pivotal support; means for moving the bracket toward the buffing wheel; means on the shaft for actuating the last said means; yielding means urging the bracket away from the buffing wheel; means drivingly connecting the prime mover with the shaft; and means for rendering the last said means ineffective after a completed cycle of rotation of the shaft.
41. A polishing machine of the character described comprising, in combination, a rotary buffing wheel; a machine frame; a slide supported by the machine frame for movement in a direction parallel to the axis of the buffing wheel; a bracket supported by the slide for movement in a direction transverse to the axis of the buffing wheel; a prime mover carried by the bracket; a rotatable shaft carried by the bracket; means for moving the slide relative to the machine frame; means drivingly connecting the last said means with the shaft; a member pivotally supported on the bracket; a workholder rotatably carried by said member remote from its pivot support so that the member is rocked toward the buffing wheel by the gravity of the workholder; means for rocking the member about its pivotal support away from the buffing wheel; means on the shaft for actuating the last said means; means drivingly connecting the prime mover with the workholder for rotating the same; means for moving the bracket toward the axis of the buffing wheel; means on the shaft for actuating the last said means; yielding means urging the bracket away from the axis of the buffing wheel; means drivingly connecting the prime mover with the shaft; and means for rendering the last said means ineffective after a completed cycle of rotation of the shaft.
42. A machine for polishing the curved surface of a workpiece comprising, in combination, a rotary buffing wheel; a machine frame; a slide supported by the machine frame for movement in a direction parallel to the axis of the buffing wheel; a table supported by the slide for movement in the direction of movement of the latter; manually operable means for moving the table relative to the slide; a bracket supported by the table for movement in a direction transverse to the axis of the buffing wheel; a prime mover carried by the bracket; a rotatable shaft carried by said bracket; means for moving the slide relative to the machine frame; means drivingly connecting the last said means with the shaft; a rotatable workholder pivotally supported on the bracket; means drivingly connecting the prime mover with the workholder for rotating the same; means for rocking the workholder about its pivotal support; means on the shaft for actuating the last said means; means for moving the bracket toward the axis of the buffing wheel; means on the shaft for actuating the last said means; yielding means for urging the bracket away from the axis of the buffing wheel; means drivingly connecting the prime mover with the shaft; and means for rendering the last said means ineffective in response to a complete cycle of rotation of the shaft.
43. A machine for polishing the curved surface of a workpiece comprising, in combination, a rotary buffing wheel; a machine frame; a slide supported by the machine frame for movement in a direction parallel to the axis of the buffing wheel; a bracket supported by the slide for movement in a direction transverse to the axis of the buffing wheel; a rotatable workholder pivotally supported on the bracket; a prime mover carried by the bracket; means drivingly connecting the prime mover with the workholder for rotating the same; a rotatable shaft carried by the bracket; means for rocking the workholder about its pivotal support; means on the shaft for actuating the last said means; means for moving the bracket relative to the slide; means on the shaft for actuating the last said means; a pair of meshing gears journaled on the slide; a driving connection between the shaft and one of the gears; a crank arm having one end journaled on the slide and drivingly connected with the other gear; a link connecting the other end of the crank arm with the machine frame; means drivingly connecting the prime mover with the shaft; and means for rendering the last said means ineffective after completion of a polishing operation.
44. A machine for polishing the curved surface of a workpiece comprising, in combination, a rotary buffing wheel; a machine frame; a slide supported by the machine frame for movement in a direction parallel to the axis of the buffing wheel; a bracket supported by the slide for movement in a direction transverse to the axis of the buffing wheel; a rotary shaft carried by the bracket; means for moving the slide relative to the machine frame; means drivingly connecting the last said means with the shaft; a rotatable workholder pivotally supported on the bracket; a prime mover carried by the bracket; means drivingly connecting the prime mover with the workholder for rotating the same; means for rocking the workholder about its pivotal support; means on the shaft for actuating the last said means; means for moving the bracket relative to the slide; means on the shaft for actuating the last said means; a clutch drivingly connecting the prime mover with the shaft; a clutch shifter rod yieldingly urged into clutch disengaging position; and means releasing the clutch shifter rod from clutch engaging position in response to a completed cycle of rotation of the shaft.
45. In a polishing machine of the character described the combination of a frame; a bracket mounted on the frame for linear movement; a crank rotatably mounted on the bracket; a link, one end of which is pivotally connected to the crank and the other end of which is pivotally mounted on the frame for rotation in a plane parallel to the plane of rotation of the crank; a rotatable shaft carried by the bracket; means transmitting rotation of the shaft to the crank; a rotatable workholder pivotally mounted on the bracket; and means on the shaft for rocking the workholder.
46. In a polishing machine of the character described the combination of a frame; a bracket mounted on the frame for linear movement; a crank carried by the bracket for rotation in a plane parallel to the plane in which the bracket moves; a link, one end of which is pivotally connected to the crank and the other end of which is pivotally connected to the bracket.

which is pivotally mounted on the frame for rotation about an axis perpendicular to the plane in which the bracket moves; a rotatable shaft carried by the bracket; means transmitting rotation of the shaft to the crank; a rotatable workholder pivotally mounted on the bracket; and means on the shaft for rocking the workholder.

47. In a polishing machine of the character described, the combination of a frame; a slide mounted on the frame for linear movement; a bracket mounted on the slide for movement transversely of the direction of movement of the slide and in a plane parallel to the plane of movement of said slide; a rotatable shaft carried by the bracket; a crank rotatably mounted on the slide; a link, one end of which is pivotally connected to the crank and the other end of which is pivotally mounted on the frame; a driving connection between the rotatable shaft and the crank, said driving connection permitting movement of the bracket relative to the slide; a rotatable workholder pivotally mounted on the bracket; and means on the shaft for rocking the workholder.

48. In a polishing machine of the character described, the combination of a frame; a slide mounted on the frame for linear movement; a bracket mounted on the slide for movement transversely of the direction of movement of the slide and in a plane parallel to the plane of movement of said slide; a rotatable shaft carried by the bracket; a crank mounted on the slide for rotation in a plane parallel to the plane of movement of the slide relative to the frame; a link, one end of which is pivotally connected to the crank and the other end of which is pivotally mounted on the frame for rotation about an axis perpendicular to the plane of movement of the slide relative to the frame; a driving connection between the rotatable shaft and the crank, said driving connection permitting movement of the bracket relative to the slide; a rotatable workholder pivotally mounted on the bracket; and means on the shaft for rocking the workholder.

49. In a polishing machine of the character described, the combination of a frame; a slide mounted on the frame for linear movement; a bracket mounted on the slide for movement transversely of the direction of movement of the slide and in a plane parallel to the plane of movement of the slide; a rotatable shaft carried by the bracket; interchangeable meshing gears carried by the slide; a crank mounted on one of the gears for unitary rotation with the same; a driving connection between the rotatable shaft and another of the gears, said driving connection permitting movement of the bracket relative to the slide; a link, one end of which is pivotally connected to the crank and the other end of which is pivotally mounted on the frame; a rotatable workholder pivotally mounted on the bracket; and means on the shaft for rocking the workholder.

50. In a polishing machine of the character described, the combination of a frame; a bracket supported by the frame for linear movement; a rotatable shaft carried by the bracket; yielding means constantly urging the bracket in a certain direction; a linkage connecting the frame with the bracket; a cam on the shaft for actuating the linkage so as to effect movement of the bracket in the opposite direction and to control movement of said bracket in said certain direction; a rotatable workholder pivotally mounted on the bracket; and a cam on the shaft for rocking the workholder.

51. In a polishing machine of the character described, the combination of a frame member; a bracket member supported by the frame member for linear movement; a rotatable shaft carried by the frame member; a linkage connecting the frame member with the bracket member, a cam on the shaft for actuating the linkage so as to cause movement of the bracket; a pulley rotatably mounted on the bracket; another pulley rotatably mounted on the frame; a cable having one end fastened to one of the members and being passed over the pulleys; a weight attached to the free end of the cable for causing the latter to keep the linkage in constant engagement with the cam; a rotatable workholder pivotally mounted on the bracket; and another cam on the shaft for rocking the workholder.

52. In a polishing machine of the character described, the combination of a frame; a bracket mounted on the frame for linear movement; a rotatable shaft carried by the bracket; a linkage connecting the frame with the bracket; a cam on the shaft for actuating the linkage so as to cause movement of the bracket; a pulley rotatably mounted on the bracket; another pulley rotatably mounted on the frame; a cable having one end fastened to the frame and being passed over the guide pulleys; a weight attached to the free end of the cable for causing the latter to keep the linkage in constant engagement with the cam; a rotatable workholder pivotally mounted on the bracket; and another cam on the shaft for rocking the workholder.

53. In a polishing machine of the character described, the combination of a frame; a bracket supported by the frame for linear movement; a rotatable shaft carried by the bracket; yielding means constantly urging the bracket in a certain direction; a linkage connecting the bracket with the frame; a cam on the shaft for actuating the linkage so as to move the bracket in the opposite direction and to control movement of the bracket in said certain direction; a rotatable workholder pivotally mounted on the bracket; and another cam on the shaft cooperating with the workholder for rocking the same in one direction and for controlling rocking of the same in the opposite direction.
